UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FOLDING DEVICE.

1,291,075.

Specification of Letters Patent. Patented Jan. 14, 1919.

Application filed April 6, 1914. Serial No. 829,911.

To all whom it may concern:

Be it known that I, JAMES R. MOFFATT, a citizen of the United States, residing at Chicago, in the county of Cook, State of Illinois, have invented certain new and useful Improvements in Folding Devices, of which the following is a description, reference being had to the accompanying drawing and to the figures of reference marked thereon.

10 The present application is a companion to those filed by me of even date herewith, serially numbered 829,912 and 829,913 and entitled respectively Sewing machine and folding mechanism therefor and Sewing machine and trimming mechanism therefor.

In those applications I have illustrated a special type of sewing machine wherein the material is fed by two feeding disks and overseamed by suitable stitch forming mechanism, the particular embodiment of such machine therein illustrated being with the folder and trimmer adapted for the formation of trousers belt loops in the making of which narrow strips of material are folded 20 with a crimped central portion, the raw edges are trimmed and forced together so that their edges meet, and are then overseamed by stitching of which the through and through stitches pass through both folded edges and catch into the crimped part of the body portion so that the raw edges are covered and united together and to the body portion and no stitches will appear on the right face of the belt loop when finished.

30 35 Inasmuch as the particular folding device devised by me may be used on other types of sewing machines than that for which it was especially designed and possesses features of novelty applicable to folding 40 devices generally, the present application for the folding device *per se* is filed.

The invention, therefore, consists among other things of a folding device having means to fold a fabric and means to initially feed the fabric forward.

It also consists in a folding device having means to fold a fabric and means which aid in positioning the material in the folder and also in initially feeding it forward through 50 the folder, until engaged by the feeding mechanism of the sewing machine.

The invention also consists in various other matters hereinafter described and referred to in the appended claims.

55 For convenience, I have illustrated my

folding device as used in coöperative relation to a cup feed overseaming machine of the type above referred to having a horizontal needle, but it will be understood that I do not wish to be limited to its application 60 to this type of machine, or this type of needle, nor to the vertical arrangement of the folder wings, as all may be varied without departing from the spirit of my invention. 65

The invention is illustrated in the accompanying drawings, in which—

Figure 1 is a perspective view of a portion of a cup-feed machine, showing my folder applied thereto;

Fig. 2 is a top plan view of the folding device and cup-feed;

Fig. 3 is a perspective view of the folder;

Fig. 4 is a longitudinal section of the same through the center of Fig. 2, with the movable member of the folder swung vertically to allow insertion of the material;

Fig. 5 is a similar view, showing the folder in position and the movable member retracted to initially position the material;

Fig. 6 is a similar view with the folder in operative position.

Figs. 7 and 8 are detail views representing the formation of blind stitched and tubular strips, respectively.

In these drawings, 1 represents a portion of the casing of a cup feed machine of the type referred to, having the two cup feeding disks 2, 2. The needle is shown at 3, the looper at 4, the deflector for both needle and looper thread loops at 5, the support for holding up the edge of the fabric at 6, the stitch finger at 7, the plate having the needle guiding groove at 8, the needle thread guides at 9, and the looper thread guides at 10. 90 All these parts are of the usual construction, and need not be more specifically referred to. A supporting bracket 11 adjustably supported on the frame of the machine by the elongated slot and screw connection 12, is 95 divided at its lower end, and has secured to it a part 13, and slot and screw connection 12 is made with the machine frame. The part 13 supports the folder and trimmer.

The folder has a stationary base 14 adjustably secured to the part 13, the openings for the screws being shown at 15. The stationary base carries the stationary side wings 16 and central fin 17. These wings extend forwardly between the cups 2, the central fin 110

well in, as shown in Figs. 2 and 3 at 34, and attached to the outside of the wide wings by screws 18, are spring fingers 19. The movable part of the folder is composed of a bar 20 formed with an arm 21 and a yoke piece 23 pivoted at 24 to the base 14. A spring 25 secured by screws 22 to the yoke piece and adapted to be engaged by a pivoted latch 26, normally holds the bar 20 from being swung upwardly.

This bar 20 carries a slidable sleeve 27, to which is attached the two spaced fingers 28, which when swung down in position, straddle the central fin 17 and coöperate therewith, and with the side wings 16 to properly fold the material as it is fed to the cups. The forward ends of the fingers 28 are toothed, as at 29, to engage the material and push it into the cups as the sleeve 27 is slid forward on the bar 20, and the inner faces of the spring fingers 19 have teeth 30 to prevent the withdrawal of the material. The spring fingers 19 also accommodate different thicknesses of material, and extend beyond the ledger blades 32 of the trimmer, as hereinafter described. A stop pin 47 limits the movement of the sleeve 27.

The operation of the folder is as follows: The latch 26 is released and the bar 20 with the sliding sleeve and fingers 28 swung upwardly; the goods are then placed in position across the stationary wings and fin of the folder, and the movable part swung down, so that the spaced fingers will straddle the fin and form the fold in the fabric. Before returning the part to its normal position, the sleeve is moved rearwardly, and when the lowered position is reached, the slide 27 is shifted along the bar 20, to push the material into the cups, so they will take hold of the same. Occasionally this movement is not enough to shift the material a sufficient distance to permit the cuts to act thereon. It is, therefore, necessary to repeat the operation, the teeth 30 at the end of the spring fingers 19 gripping the material and preventing it from being pulled back with the return movement of the sleeve 27.

It will thus be seen that the movable part not only coöperates with the stationary part to fold the material to proper shape to have the edges overseamed, but also enables the operative to initially position the material between the cups. The bodily vertical adjustment of this folding device through the slot and screw adjustment 12, enables the bite of the needle into the goods to be varied, so that it may either engage the portion of the fabric which is pressed up from the center by the fin 17 coöperating with the spaced fingers 28, thus overseaming the edges and uniting them to the body fabric at the center, as in Fig. 7, or simply uniting

the edges and overseaming them, as in Fig. 8, making a tube.

A gage 35 composed of a suitably graduated nut bears on the ledge 36 formed on the vertical part of the bracket 11, and by manipulating the same, the precise adjustment desired may be secured.

In connection with this folder, I have devised a trimming device including a horizontal trimming blade 31, which reciprocates back and forth and acts in connection with stationary ledger blades 32 which form extension of the side wings 16 to trim off the surplus material, the trimming mechanism as a whole being supported on the same bracket as the folder, and partaking of the adjustments of the latter. It also has a deflecting plate 33 to deflect the trimmed-off strips.

Having thus described my invention, what I claim as new and desire to secure by Letters Patent, is:

1. A folding device comprising stationary side wings and a central fin, a pivoted member, a member slidable on said pivoted member and carrying wings for coöperation with the wings in the folder to fold the material and initially feed it forward.
2. In a folding device, means to fold a fabric, and a manually operated coöperating device acting on one face of said fabric to first position the same in said folder and subsequently feed it forward.
3. A folding device for sewing machines, including a stationary part having folding projections, and a vertically movable part having devices coöperating with the folding projections to properly fold the fabric, said vertically movable part being arranged also to permit a horizontal movement to initially position the goods.
4. A folding device for sewing machines comprising a stationary base portion having wings thereon, a coöperating finger portion movable laterally toward and from said wings to complete the fold in the fabric and also movable in a direction lengthwise of the folding device to feed the fabric forward.
5. A folding device for sewing machines comprising a stationary base portion having wings thereon, a coöperating finger portion movable laterally toward and from said wings to complete the fold in the fabric and also movable in a direction lengthwise of the folding device to feed the fabric forward, said finger portion having teeth thereon to engage the fabric.
6. A folding device for sewing machines, comprising a stationary base portion having wings thereon, a horizontally slidable coöperating finger portion adapted to complete the fold in the fabric and feed it forward to initial position, said horizontally slidable portion having teeth to engage the

fabric, and toothed spring portions extending in rear of the stationary wings to engage and hold the material against displacement.

- 5 7. A folding device for sewing machines, comprising stationary wings, a member pivoted to swing vertically, a member slidable on said pivoted member and carrying wings coöperating with the stationary wings to fold the material.
  - 10 8. A folding device for sewing machines, comprising stationary wings, a member pivoted to swing vertically, a member slidable on said pivoted member and carrying wings coöperating with the stationary wings to fold the material, and a latch for holding said pivoted member in normal position.
  - 15 9. A folding device for folding narrow strips of material, comprising spaced stationary projecting wings and an intermediate crimping fin, and a coöperating movable folding member adapted to engage and crimp and fold the material, and means permitting it to be moved longitudinally to initially feed the material.
  - 20 25

10. A folding device for folding narrow strips of material, comprising spaced stationary projecting wings, and an intermediate crimping rib with means coöperating therewith to fold the strip into a **W**-formation with the opposite edges higher than the central crimped portion, said crimping rib being arranged to crimp the material in a line which will be crossed by the needle of the sewing machine to which folding device is to be applied.

11. A folding device for folding narrow strips of material, comprising spaced stationary projecting wings, and an intermediate crimping rib with means coöperating therewith to fold the strip into a **W**-forma-

tion with the opposite edges higher than the central crimped portion, said crimping rib being arranged to crimp the material in a line which will be crossed by the needle of the sewing machine to which the folding device is to be applied, and means coöoperating with the projecting wings to force the edges of the strip together, whereby the needle will enter the edges and crimped portion. 50

12. A folding device for sewing machines comprising a stationary base portion having wings thereon, a pivoted horizontally slid-
able coöperating wing portion to complete the fold in the fabric and to feed it forward 55 to initial position, with a stop for limiting the movement of said slidable portion.

13. A folding device for sewing machines comprising stationary wings, a member pivoted to swing vertically, a member slidable on said pivoted member and carrying wings cooperating with the stationary wings to fold the material, and a stop on said pivoted member for limiting the movement of said slidable member. 60 65

14. The combination with a feeding mechanism, of a folder operating upon a strip to fold the same as it is drawn through the folder by the feeding mechanism, said folder having a movable section which may be moved away from the other part of the folder to permit the insertion of the strip, said movable section of the folder being movable lengthwise of the folder for initially positioning the strip for engagement, by said feeding mechanism. 75

"In testimony whereof, I affix my signature, in the presence of two witnesses.
